REMOTE CONTROL SYSTEM

Filed April 2, 1928

UNITED STATES PATENT OFFICE

MARTIN L. NELSON, OF PARK RIDGE, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

REMOTE CONTROL SYSTEM

Application filed April 2, 1928. Serial No. 266,827.

The present invention relates in general to remote control system, more specifically to such systems in which devices at a plurality of points are controlled over one common trunk line, and the principal object of the invention, briefly stated, is the production of a new and improved remote control system of this type, the improvements permitting greater flexibility of operation without increasing the initial cost and maintenance expense.

In commercial installations, it frequently happens that there are a large number of switching devices to be controlled, and that these switching devices are widely distributed, that is, there are but one or two of the devices at any one point. For example, along a railroad line there may be a plurality of semaphores or lamp operated track side signals, distributed throughout the length of the railroad. At any one point, there will be only one or two of these signals, and it is to the selection and control of the signals in a system of this kind that this invention is directed. Similarly in a power distribution system, a transmission line may radiate out from a power station, and have a plurality of feeder circuit breakers connected to it at various distributing points, there being but one breaker at each of these points. A dispatcher located at a central point in either of the above systems, may desire to select and operate any one of the devices along the route. In accordance with established practice in systems of this kind, after the dispatcher has made the selection, he must receive a check-back indication to advise him of the fact that his selection has been accurately made. After receiving this check-back further operating is required on the part of the dispatcher to control the selected device.

As an object of the present invention, I provide a new and improved remote control system of the tandem type, in which the check-back indication is given audibly, that indication serving not only to indicate the position of the selecting switch, but by means of varied tone signals indicates the actual position of the selected device.

As a further object of my invention, I pro-

vide circuit arrangements which enable the dispatcher to select a device, and to operate it a plurality of times without releasing his selecting switch and reoperating it to reselect the device.

This and other objects not specifically mentioned will be best understood from the reading of the detailed description and claims which follow.

The drawing, shows a sufficient detail to enable a clear understanding of my invention. The dispatcher's station R comprises a calling device 30, battery 31, hook switch 32, telephone receiver D and a condenser. The calling device is preferably of the type commonly used in automatic telephone systems.

Leading out from the dispatcher's station D is a two-wire trunk, across which trunk are bridged the line relays of each of the substations. The substation A, which is shown in full, comprises the selecting switch H, the control relays 9 to 13 inclusive which are adapted to be selected by the control switch H and operated to control the lamp signals 79 and 80. Associated with the control switch is the counting switch CS which is operated responsive to an operation of the switch H to send back over the trunk a code of audible impulses indicating the number of the bank contacts upon which the connecting switch H is resting. The connecting switch H is preferably of the type of the well known connector switch used in automatic telephone systems, a switch which is shown on page 11 and described upon the succeeding pages of the book "Principles of Automatic Telegraphy" by Harry P. Mahoney. This switch, comprises a shaft carrying a group of wipers, which are moved first in a vertical direction responsive to one digit received by the switch to select a level in the bank, and then in a horizontal direction to select a contact in that level. The bank comprises 100 contact sets, arranged in ten rows or levels with ten contacts in each row. The circuits of the switch H are varied from the standard connector in accordance with the objects of the present invention.

The counting switch CS is a mechanism similar to the rotary lineswitch of the auto-

matic telephone system, with the wipers of the switch replaced by the cams which control springs 68 and 69. A switch of this type, is shown in Fig. 45 on page 38 of the 5 above referred to text book.

For the purpose of example, the lamp 80 is assumed to be the green lamp of a lamp signal located along the side of a railroad track, and is lighted at the present moment 10 to indicate a clear track. If the dispatcher at the station D desires to alter this signal, he removes the receiver R from the switchhook, operates the calling device in accordance with the digits of the station controlling 15 the lamp 80. Assume for the moment that this is station #62, the dispatcher will dial a 6 followed by a 2. Responsive to the reception of the 6, the connecting switch H will elevate the wipers 55 and 56 six vertical steps, 20 and responsive to the receipt of the digit 2 will rotate these wipers two steps in a horizontal direction into engagement with the contacts through which the lamp 80 is controlled. The positioning of the switch H 25 upon the contacts 62 actuates the code sending switch CS which is arranged to transmit the digits 6—2 back to the dispatcher to advise him of the correct positioning of the switch wipers upon the desired set of contacts. Since the lamp 80 is lighted, the tone 30 which the dispatcher hears will be generated by the low pitch buzzer 25, the receipt of that low pitched tone indicating to the dispatcher that the lamp 80 is burning. Upon hearing 35 this check-back signal, the dispatcher reoperates his calling device 30 to transmit another digit whereupon the relays 9 to 13 are actuated to extinguish the lamp 80 and to light the lamp 79. The dispatcher is informed 40 that the green lamp 80 has been extinguished and the red lamp 79 lighted by a change in the tone which he receives back from the substation. The operation of relay 9 actuates springs 58, which cuts off the low 45 pitch buzzer 25 and inserts in its place the high pitched buzzar 26. The dispatcher then hears the code 6—2 in a high pitch, informing him that the signal has been set to red or danger. If for any reason the dispatcher desires to 50 reset the signal to clear, that is to re-light the green lamp 80, he merely sends another digit by manipulating his calling device, whereupon the relays 9 to 13 are reoperated to extinguish the red lamp 79 and light the green 55 lamp 80. The pitch of the tone which the dispatcher hears is altered by the operation of springs 58, so that the new signal comes in in a low pitched tone generated by the buzzer 25.

In the other substations along the trunk, 60 such as substation B, the line relay 27 follows the impulses generated by the calling device, and the connecting switch H' is stepped up and around to its 62nd branch contact position. However, the substation A 65 is the only substation having circuits extend-

ing from the bank contact 62, so that the operation of the connecting switch H', and the other connecting switches on the trunk are without effect.

Having thus described my invention in general, I will now proceed with a detailed description of its operation. 70

Calling substation A

When the dispatcher removes the receiver R from the switchhook, a circuit is closed 75 from the positive pole of battery 31, through switchhook springs 32, right hand trunk conductor, through the winding of the relay 1, substation A, resistance 33; to the left hand trunk conductor, thence back through the calling device 30 to the negative pole of the battery 31. In the substation B, there is a path across the two trunk conductors in multiple with the relay 1, that path including 80 the relay 27 and the resistance 27'. Similarly in each of the other substations a line relay and a resistance are bridged across the trunk. The battery 31 is of such a potential that it 85 will supply a sufficient current to each of the relays 1 and 27, etc., to properly operate these relays. The resistance 33 and 27', etc., are included in the circuit and are adjusted so that the corresponding relay receives the 90 correct amount of current for its proper functioning. 95

The energization of the line relay 1 in substation A closes a circuit from ground through springs 41, through the winding of the slow to release relay 2 to battery. This 100 relay 2, being equipped with a copper slug on the heel end of its core, indicated by the cross-hatched section on the drawing, is made slow to release and will remain energized during the transmission of impulses over the trunk circuit. The energization of relay 2 at 105 springs 40 closes a control circuit for the relay 5 which is ineffective at the present time. At springs 43, relay 2 opens a point in the circuit of the release magnet 15, and prepares 110 a point in the impulsing circuit of the switch H.

When the dispatcher operates his calling device 30 to transmit the digit 6, that being 115 the first digit of the substation A, line relay 1 falls back six times, as does the line relay 27 of the substation B and the line relays of each of the other substations on the trunk. Responsive to the deenergization of a line 120 relay 1, spring 41 opens the circuit of relay 2, which remains energized, and closes the circuit from ground through spring 41 and its break contact, spring 43 and its make contact, off normal spring 42 and its break contact, through the winding of relay 3, the 125 winding of the vertical magnet 14 to battery. The relay 3 and the vertical magnet 14 energize over this circuit. The vertical magnet 14 raises the shaft carrying wipers 55 and 56 one vertical step, operating the off-normal 130

springs 42 and 44. The relay 3 energizes and because of the copper slug on the heel end of its core remains in its energized position during the impulsive, and at springs 45 closes an auxiliary circuit for itself and the vertical magnet. At the end of the first impulse, relay 1 reenergizes, opening the circuit of vertical magnet, which falls back and reclosing the circuit of the release relay 2 which has remained energized. The second impulse traverses a circuit extending from grounded spring 41 and its break contact, spring 43 and its make contact, off normal spring contact 42 and its make contact, spring 45 and its make contact, thence through the winding of relay 3 and the vertical magnet to battery. The remaining four impulses of the digit 6 are transmitted over this latter circuit without change, at the end of which time the shaft carrying the wipers 55 and 56 is standing opposite the sixth level of the bank.

When the calling device 30 has returned to normal after the transmission of the last vertical impulse, line relay 2 comes to rest energized, and the circuit of the vertical magnet and the relay 3 is open a sufficiently long time to permit the relay to deenergize. When the dispatcher transmits the digit 2, the second digit of the called number of the substation A, line relay 1 falls back twice, each time transmitting an impulse over the circuit including spring 41 and its break contact, spring 43 and its make contact, off normal spring 42 and its make contact, spring 45 and its break contact, thence over parallel paths, the one including the winding of the slow to release relay 4 to battery, the other the springs 49 and its break contact through the winding of the rotary magnet 16 to battery. Relay 4 energizes and remains energized during the transmission of the impulses, magnet 16 energizes and deenergizes with each impulse, each energization advancing the wipers one step in a rotary direction.

The energization of relay 4, closes a circuit from grounded springs 46 and its make contact, springs 48 and its break contact, through the winding of relay 6 to battery, energizing the relay 6. Relay 6 at springs 51, prepares a point in the circuit of relay 5, however, relay 5 is short circuited at the moment, having ground placed upon its lower terminal by the springs 40 of relay 2, and upon its upper terminal by the springs 46 of the relay 4.

After the transmission of the digit 2, the wipers 55 and 56 are resting upon this 62nd bank contact set that is the set shown in the drawing leading to the control relays of the substation A. Relay 4 deenergizes a brief interval after the transmission of the last impulse, and at springs 46 removes the short circuit from the relay 5, which energizes over a circuit extending from ground

on springs 40, through relay 5, through springs 51, through relay 6 to battery. Relay 6 is maintained energized over this circuit. The energization of relay 5, at springs 49, opens a point in the circuit of the rotary magnet, so that the transmission of further impulses to the switch will not move the wipers. At springs 48, relay 5 opens the initial energizing circuit of relay 6, without effect at this time since that relay is maintained energized through springs 51. At springs 47, relay 5 prepares a point in the circuit of wiper 55, that circuit being open at the present time at springs 46 and 52.

80

The check-back signal

The energization of relay 5 closes springs 50, thereby closing a circuit from ground through the wiper 56 and the winding of the relay 24 to battery. Relay 24 energizes over the circuit and at springs 73 closes a circuit from ground through spring 58 and its break contact, through the winding of the buzzer 25, through the primary winding 82 of the induction coil to battery. Buzzer 25 energizes over this circuit, attracting the armature 76 which short circuits the winding 25 of the buzzer. The short circuiting of the winding 25 causes the armature 76 to be retracted, whereupon the short circuit is removed and the armature 76 reattracted. Thus it will be seen that the magnet 25 will alternately energize and deenergize, at a speed dependent upon the characteristics of the magnet 25 with respect to the armature 76. This characteristic is one which gives a slow energization of the magnet 25. When the magnet 25 is in series with the winding 82 of the induction coil, a relatively small amount of current is flowing through that induction coil. When the armature 76 short circuits the magnet 25, the current increases in the winding of the induction coil. This variation of current in the primary winding of the induction coil induces in the secondary winding 81 a voltage which drives current over a circuit to be subsequently closed, to place a tone back upon the trunk conductor to advise the dispatcher of the position of the switch. Since the buzzer 25 is a low pitched buzzer, the current in the secondary winding 81 will be of low frequency and the tone a low pitched tone.

110

The energization of relay 24 closes a circuit from ground through springs 72, through spring 67 and its break contact, through the winding of relay 22 and the resistance 23 in parallel to battery. Relay 22 energizes over this circuit, and at springs 71 closes a circuit from ground on springs 72 through the relay 20 and the resistance 21 in multiple. Relay 20 energizes over this circuit and at springs 70 closes a circuit from ground on springs 72 through the relay 18 and the resistance 19 in multiple. Relay 18 energizes and at springs

130

67 opens a point in the circuit of relay 22, and closes a circuit to the motor magnet 17, which energizes preparatory to advancing the cams 68' and 69' one step. Relay 22 being slow 5 to release because of the copper slug upon the heel end of its core, indicated on the drawing by the cross sectioned area, is not immediately deenergized but remains energized for a brief interval. When relay 22 deenergizes it opens a circuit of relay 20 which is likewise slow to release. When relay 20 deenergizes it opens the circuit of relay 18 which deenergizes relatively quickly, and opens the circuit of the magnet 17 which deenergizes and advances the cams one step. The deenergization of relay 18 likewise recloses the circuit of relay 22 which is again operated. Advancement of the cam 69' in this direction indicated by the arrow, closes 10 the springs 69, closing a circuit from ground to the springs 67, 70 and 71 in multiple with the ground placed on by springs 72, so that if the dispatcher should hang up before the code switch has reached its normal position 15 relays 18, 20 and 22 will interact from ground on springs 69 until the cams are positioned in their normal position. When the cam 68' advances one step, it closes the springs 68, thereby closing a circuit from spring 75 and 20 its make contact, springs 74 and its make contact, springs 68, the condenser, right hand trunk conductor, hookswitch springs 32, the receiver R, the condenser, left hand trunk contact, through the winding 81 of the induction coil. The tone induced in the winding 25 of the induction coil by the buzzer 25 is thereby made audible to the dispatcher through the receiver R. As the code switch CS advances, springs 68 are closed 6 times, 25 then there is a pause equal to two steps of the code switch, and then the springs 68 are again closed two times. The dispatcher therefore hears the code 6 pause 2, in a low pitched tone, which informs him that he has 30 selected the device 62, and that that device is in its normal position.

Operating the selected device

After the dispatcher has listened to the 35 code indication long enough to determine whether or not he has selected the desired set of contacts and whether or not the selected device is in the position that he thinks it is, he may alter the position of the selected device by reoperating his calling device to 40 transmit a digit. The operation of the calling device opens the circuit of the line relays, the line relay 1 falling back to again close the impulsive circuit at springs 41. Since 45 the off normal springs 42 and the relay 5 are in their energized position, closing of the impulsive circuit does not energize either of the motor magnets of the switch H, and the wipers are not moved. A circuit is closed, 50 however, from ground on spring 41, through

spring 43 and its make contact, off normal spring 42 and its make contact, springs 45 and its break contact and thence over parallel paths, one through the winding of slow to release relay 4, to battery, and the other through spring 49 and its make contact, spring 53 and its break contact, through the winding of relay 8 to battery. The energization of relay 4 over this circuit, closes at 55 springs 46 a point in the circuit of relay 7, however, the relay 7 does not energize at this time. The energization of relay 8, at springs 54 closes another point in the circuit of relay 7, to short circuit that relay during the time of the impulse that the relay 1 is deenergized. 60 When the relay 1 pulls up at the end of the first impulse of the digit dialled by the dispatcher, the short circuit is removed from relay 7, and that relay energizes over a circuit traceable from ground to springs 46, relay 7, 65 springs 54, and the winding of relay 8 to battery. Relay 8 is maintained energized in series with relay 7 over this circuit. Relay 7 at springs 53 opens the initial energizing circuit of relay 8, to prevent another impulse 70 from short circuiting relay 7. At springs 52 relay 7 closes a circuit to the wiper 55. The additional impulses of the digit dialled by the dispatcher merely go through the winding of relay 4 to battery to maintain that 75 winding energized for a short interval of time. A circuit may now be traced from ground on spring 46, through springs 47, springs 52, the wiper 55, and the 62nd bank contact that it is engaging, springs 57 and its 80 break contact, through springs 61, through the winding of relay 10 to battery. Relay 10 energizes over this circuit, and at springs 59 opens a point in the circuit of relay 11. At springs 83, relay 10 locks itself through 85 the ground placed on the bank contact by wiper 55, independently of the springs 57 and 61. At springs 60, relay 10, closes a circuit from ground to the winding of relay 12 to 90 battery, energizing the relay 12 which locks itself through springs 64 and 65 to ground. The energization of relay 12, operates springs 95 66, to extinguish the green light and to light the red lamp 79 over circuit from ground, through spring 66 and its make contact, through the lamp 79, through the winding of relay 9 to battery. Relay 9 is of low resistance and does not materially dim the lamp 79. The energization of relay 9, at 100 springs 57 opens a point in the circuit over which relay 10 was energized, without effect at this time since relay 10 is locked through springs 83 independently of these contacts. At springs 58, relay 9 opens the circuit of 105 the low pitched buzzer 25, and closes a circuit of high pitched buzzer 26, the latter buzzer operating to energize the primary winding 82 of the induction coil in the hereinbefore explained manner. The dispatcher, will 110 therefore be advised of the operation of the 115 120 125 130

lamp signals by a change in the pitch of the code that he receives. He will now receive a high pitched 6 pause 2, to inform him that the red light at substation A is burning.

5 When the calling device 30 returns to its normal position, relay 1 comes to rest energized, and the circuit of relay 4 is open. Relay 4 deenergizes after a brief interval, unlocking at springs 46 the relay 10 of the 10 selected signal and the relays 7 and 8 of the switch H. Relay 10 falls back, and at springs 59 prepares a point in the circuit of the relay 11. At springs 60 relay 10 opens the circuit of relay 12, however, relay 12 remains energized since it is locked through springs 64 and 65. In the switch H, relays 7 and 8 deenergize for a purpose which will be explained presently. The result of the dispatcher having dialled the digit after he selected the device 62 is to energize the relay 9, and to energize the relay 12, both of which are held up pending further operation on the part of the dispatcher. The red light 79 is lighted and the green light 80 is extinguished.

25 Assume now that the dispatcher after having set the red lamp at the substation A decides to erase his operation and restore the signals to the position they previously occupied. To do this he again dials a digit 30 operating the relays 7 and 8 in the herein-before explained manner, and operating the relay 4 as before. A circuit may now be traced from ground through spring 46, springs 47 and 52, wiper 55 through spring 35 57 and its make contact, 59 and its break contact, through the winding of relay 11 to battery. Relay 11 energizes over this circuit, and at springs 62 locks itself to the ground placed on the contact engaged by wiper 55 40 independently of the springs 57 and 59. At springs 61, relay 11 opens a point in the circuit of relay 10. At springs 63, relay 11 closes a circuit for the relay 13 which energizes. At springs 65, relay 13 opens the locking circuit 45 of relay 12, permitting that relay to deenergize. The deenergization of relay 12 permits spring 66 to break away from its make contact and engage the break contact, thereby extinguishing the lamp 79 and permitting 50 the relay 9 to deenergize, and lighting the lamp 80. The deenergization of relay 9 prepares at springs 57 a point in the circuit over which the relay 10 was energized, and at springs 58 disconnects the high pitched buzzer 26 and connects in its place the low pitch buzzer 25. The dispatcher upon hearing the code 6-2 in a low pitched tone knows that the signals at substation A have been 55 restored to their initial condition.

60 When the calling device returns to normal, and relay 1 comes to rest energized, the circuit of relay 4 is opened as before, relays 7 and 8 are restored, relay 11 is restored, and relay 13 is restored, thereby restoring the

equipment to the position occupied in the drawing in which position it is normal.

If the dispatcher again changes his mind, decides that he wants the red lamp 79 operated, he merely has to reoperate the calling device to again extinguish the green lamp 80 and light the red lamp 79, the operation being supervised by a change in the pitch of the tone of the code that he receives.

Release

When the dispatcher has completed the operations that he sets about to do, he releases the circuit by replacing the receiver on the hook switch, to break at springs 32 the circuit of the line relay 1 of the station A the line relay 27 at the station B and the other line relays bridged across the trunk conductors. Relay 1 falls back, opening the circuit of relay 2, which after an interval falls back and at springs 43 closes the circuit to the release magnet which is traceable from ground to springs 41 and its break contact, springs 43 and its break contact, off normal spring 44 and its make contact, through the winding of release magnet 15 to battery. The release magnet energizes and withdraws the retaining pawls from the shaft, not shown, permitting the shaft to restore to its normal position, disengaging the wipers 55 and 56 from the bank contacts. The deenergization of relay 2 opens at springs 40 the locking circuit of relays 5 and 6, permitting those relays to restore the switch H to its normal position. When the shaft has returned to normal, off-normal springs 42 and 44 are operated, the latter to open the circuit to the release magnet, thereby completing the restoration of the switch H. The switch H' in the substation B is similarly released as is the selecting switch in each of the other substations on the trunk.

While I have chosen to show my invention in connection with a particular class of apparatus, I have done so by way of example only, as there are many modifications which will be apparent to one skilled in the art which can be made without departing from the scope and spirit of my invention. I have chosen to illustrate the invention in connection with the control of a pair of lamp signals, it being obvious that the lamp signals could be replaced by operating magnets to control either a semaphore, a circuit breaker, or any other piece of electromagnetic equipment.

Having thus described my invention, what I consider new and desire to have protected by Letters Patent is pointed out in the appended claims.

What is claimed is:

1. In a signalling system, a device having a plurality of positions, a tone generator for each position of said device for generating tones of different pitch, a circuit closer asso-

ciated with said device, means for selecting said device, means responsive to said selection for operating the tone generator which is controlled by the position occupied by said device and for operating said circuit closer, and means in said circuit closer for interrupting the tone generated by said tone generator to transmit coded audible tone impulses which indicate by the number of coded impulses the device selected and by the pitch of the tone the position of the device.

2. In a signalling system, a device having a plurality of positions, a tone generator for each position of said device for generating tones of different pitch, a circuit closer associated with said device, means for selecting said device, means responsive to said selection for operating the tone generator which is controlled by the position occupied by said device and for operating said circuit closer, means in the circuit closer for splitting the tones generated by said generators into coded audible tone impulses which indicate by the number of coded impulses the device selected and by the pitch of the tone the position of the device, means for operating said device from one position to another position, and means responsive to said operation for stopping the said operating tone generator and for operating another of said generators whereby the tone of the code impulses is altered to indicate the altered position of said device.

3. In a signalling system wherein an electromagnetic device having a plurality of positions is adapted to be operated from position to position, means for transmitting an audible code signal of variable tone and predetermined code which simultaneously indicates the said device and its occupied position, and means responsive to each change in position of said device for altering only the tone of said signal to indicate the new occupied position of said device.

4. In a remote control system, an electromagnetic device having a plurality of positions, a control switch, a calling device for transmitting a variable number of impulses of uniform duration in each successive operation thereof, means responsive to the first series of impulses transmitted by the first operation of said calling device for directly operating said switch to select said device, means for thereafter maintaining said switch in its selecting position during successive series of impulses transmitted by the successive re-operations of said calling device, and means in said switch thereafter responsive to the successive series of impulses transmitted by the successive re-operations of said calling device for successively changing said device to alternate positions.

5. In a remote control system, a circuit breaker having a first and a second position, means for operating said circuit breaker to

its first position, means for operating said circuit breaker to its second position, a control switch, a calling device for transmitting a variable number of impulses in each successive operation thereof, means responsive to the first series of impulses transmitted by the first operation of said calling device for directly operating said switch to select said device, means for thereafter maintaining said switch in its selecting position during successive series of impulses transmitted by the successive re-operations of said calling device, and means in said switch thereafter responsive to alternate series of impulses transmitted by alternate re-operations of said calling device for operating said first means to operate the device to its first position and responsive to the intermediate alternate series of impulses transmitted by the intermediate alternate re-operations of said calling device for operating said second means to operate the device to its second position.

In witness whereof, I hereunto subscribe my name this 30th day of March, A. D. 1928.
